GEORGE W. KUENNETH, OF PATERSON, NEW JERSEY, ASSIGNEE, BY MESNE ASSIGNMENTS, TO JEANNETTE KUENNETH, OF PATERSON, NEW JERSEY.

BEAMING MACHINE.

1,412,877.

Specification of Letters Patent. Patented Apr. 18, 1922.

Application filed December 3, 1918. Serial No. 265,127.

To all whom it may concern:

Be it known that I, GEORGE W. KUENNETH, a citizen of the United States, residing at Paterson, in the county of Passaic 5 and State of New Jersey, have invented certain new and useful Improvements in Beaming Machines, of which the following is a specification.

This invention relates to beaming machines, and particularly to machines for beaming warps which have been laid spirally on the reel of the machine in warping, as in spiral sections by the so-called Swiss horizontal warping method.

15 My invention contemplates principally the following improvements: (1) A novel arrangement and construction of the traversing beam carriage, its supporting means and transversing means and the means to rotate 20 the beam; (2) a novel mounting for the beam in the carriage; (3) the provision of a novel beam-carriage supporting means in combination with the frame of the machine, whereby an old-style frame may be adapted 25 to receive a longer beam and thus accommodate the more modern and wider warps; (4) novel means for driving and controlling the rotation of the beam; and (5) novel means 30 for disconnectively connecting the reel shaft with the rotary feed-screw (of the carriage traversing means) for purposes to be explained hereinafter in detail.

In the accompanying drawings,

Figure 1 is a side elevation and Figure 2 35 an end elevation of a warping and beaming machine embodying my improvements, the end of the machine which is devoted to warping being broken away in Figure 1;

Figure 3 is a plan of the beaming end of 40 the machine;

Figures 4, 5 and 6 are a plan and side and end elevations of one of the brackets forming part of the extension frame for the beam and its accessories;

45 Figures 7 and 8 are sectional views on lines 7-7 and 8-8 of Figure 3;

Figure 9 is a side elevation of a certain clutch-lever;

Figure 10 is a sectional view on line 50 10-10, Figure 7;

Figures 11 and 12 are sectional and side views, respectively, of a coupler-head on the reel-shaft;

Figure 13 is a sectional view on line 55 13-13, Figure 3;

Figure 14 is a side elevation of what appears in Figure 13;

Figure 15 is a sectional view on line 15-15, Figure 3;

Figure 16 is a side elevation of what appears in Figure 15;

Figure 17 is a sectional view on line 17-17, Figure 3;

Figure 18 is a side elevation of what appears in Figure 17; and

Figure 19 shows in end and side elevation, partly in section, a certain nut.

In the frame *a* is journaled the reel *b* adapted to be driven, when warping, through the medium of a belt-and-pulley connection, 70 generally denoted by the character *c*, from one of a pair of pulleys 17-18 (to be described) when by means of the lever *d* the pulley *e* of such connection is shifted into contact with the driving wheel or band *f* of the reel, all in the usual manner. The usual 75 brake-strap *f'* is provided to resist rotation of the reel, the same bearing against the band *f*. One end of the reel shaft *b'* carries a sprocket-wheel *g* affording part of a 80 sprocket-and-chain connection for transmitting traverse motion to the reed-carriage (not shown) of the machine, as usual, when it is being used for warping. The other end of said shaft carries the hereinbefore-mentioned coupler-head, to be described in detail. There is shown in Figures 1 and 2 a certain means *h* to maintain control of the warp; but this is not at all concerned with the present invention. I reserve it for 85 another application.

The frame *a* shown is the well-known old-style wood frame. Modern frames, because modern warps are prepared in greater width than formerly, are not adapted to 95 receive beams capable of accommodating such warps and at the same time of having the necessary traverse if it is sectional warping and beaming that is to be performed. Wherefore I fit to the frame an extension 100 frame constructed as follows: There are two brackets *i* in each consisting of a body-portion *j*, which is bolted to the end of the frame *a* and is flanged at the top to overhang and obtain a bearing on the same, 105 and an arm *k* integral with and projecting first laterally and then forwardly from the part *j*, the two brackets being reverse counterparts of each other (so that there is materially greater distance between their arms 110

k than between the sides of the frame *a* excepting that the near bracket in Figure 1 has upward and downward projections *l* and *m* (Figures 4 and 5). Legs *m'* may 5 support these brackets.

In these brackets are secured the guide- 10 rods *n* on which the beam-carriage traverses. On the guide rods is secured a cross-head *o*, arranged a suitable distance from the right-hand bracket *i*.

The carriage comprises two heads *p* and *q* apertured to receive and slide on the guide rods and connected by the tie-rods *r* which are preferably fixed in say the head *p* and 15 adjustably held in the head *q* by the set screws *s* so that the two heads may be set different distances apart. On the basal or body part of the head *p* is bolted, supported by the adjusting screws *t*, a bracket *u* in 20 which, by set-screws *v*, are secured the horizontal studs *w*, on which is in turn secured, by the set screw *x*, a bracket *y*. This construction permits not only the effective 25 height of the head *p* to be altered in leveling-up the beam but its superstructure to be moved horizontally relatively to its basal part, for a purpose to be explained. The other head *q* forms a narrow upright 30 housing, the top part of which may form a removable cover *q'*, and in it is journaled a tubular shaft *z* having keyed on it a gear wheel 2 and protruding at the inside and having suitably secured thereto the arm 3 to which is attached the beam-lashing 4.

35 The beam 5 has its trunnions set in a bearing in the bracket *y* and in the tubular shaft *z*, being adapted to be secured to arm 3 by the lashing 4.

In the bracket *i* and the cross-head *o* is 40 journaled the drive-shaft 6 carrying a bearing head 7, which is keyed to the shaft and holds it against left-hand movement. In the bracket *i'* and said cross-head is journaled the feed-screw 9, held against longitudinal movement by a collar 10 and a sprocket wheel 11; this sprocket-wheel preferably has a handle 12.

The drive-shaft 6 carries, splined thereon and confined in the housing of head *q* between its two side walls, a pinion 14 in mesh 50 with the gear wheel 2. Engaged with and penetrated by the feed-screw 9 is a nut 15 which is confined between opposite walls of the basal part of head *p* and held against 55 turning by the pin 16.

On the bearing-head 7 are journaled, integral with each other, the hereinbefore-mentioned stepped pulley, 17, and the main drive pulley 18. In slots therein the bearing-head has keys or wedges 7', whereby to establish a frictional interlock or clutch between the bearing-head and pulley structure upon pushing inwardly against said 60 keys a thrust-piece 19 suitably tapered at 65 its inner end to cam the keys outward

against the bore of said pulley structure. This wedge-piece is normally retracted by a spiral spring 20 interposed between the bearing-head and a shoulder on the wedge-piece. Its inward movement is adapted to 70 be effected by a lever 21, journaled in an overhanging arm 21' bolted to the projection *l* of bracket *i* with which the wedge-piece has a swivel connection as shown in Figure 9, when the lever is actuated from 75 a treadle 22 extending across the machine through the medium of a chain 23 connecting the treadle with a sprocket-wheel 24 journaled in a bracket 25 bolted to the projection *m* of bracket *i*, and a chain 26 connecting said sprocket-wheel and lever.

On the drive-shaft 6 is secured a ratchet-wheel 27. A pawl 28 coacts with this ratchet-wheel to prevent backward rotation of the beam when, on releasing treadle 22, the power is cut off from the drive-shaft 6, leaving the tension of the warp (since the reel is held by brake-strap *f'*) otherwise free to cause reversal of the beam. In previous beaming machines such pawl clicks idly over 90 the teeth of the ratchet-wheel when the latter is rotating, but in my construction it is held clear of the ratchet-wheel at that time and only engages therewith when the power is cut off and the beam is to stop, thus to 95 avoid undesirable noise. The pawl, 28, is fulcrumed on one of the guide-rods and a spring 29 tends to hold it against the ratchet-wheel. But a flexible connection 30 extending over a suitable sheave 31 and connected 100 to the sprocket-wheel 24 is caused, whenever treadle 22 is depressed to establish the power, to retract the pawl. In consequence the pawl is always clear of the ratchet-wheel while the latter is in motion, though it engages the 105 same as soon as it stops.

The hereinbefore-mentioned coupler-head comprises a sleeve 32 pinned to the reel shaft *b'* and supporting, in axial alinement with the reel shaft, a bearing stud 32', which 110 protrudes from the sleeve. Pinned on the bearing stud is a cross-head 33 equipped on one arm with a pivoted spring-pressed pawl 34 and on the other with a radially adjustable toothed dog 35, 35' being a bolt to clamp the 115 dog in any position to which it is adjusted and being received in a radial slot 35" in the cross head; said coupler-head further comprises, revoluble on the stud 32', a combined sprocket-wheel 36 and ratchet 37, the latter 120 being engaged by the pawl 34 but not (normally) by dog 35, which usually stands retracted—not as shown in Figures 11 and 12. A sprocket-chain 38 extends around the sprocket-wheel 36 and sprocket-wheel 11. In 125 a hole 39 in the cross-head a pin or equivalent detent may be introduced to hold the pawl clear of the ratchet at certain times.

Operation: It will be understood that in order to rotate the beam in beaming it is only 130

necessary to hold the treadle depressed to establish the clutch between the suitably driven pulley structure 17—18 and the bearing head 7; this, as explained, disengages the 5 pawl 28 from ratchet 27, which is held disengaged so long as the treadle remains depressed, but returns into engagement when pressure on the treadle ceases. While the beam and consequently the reel are thus rotated 10 in beaming pawl 35 turns the ratchet and sprocket-wheel 37—36 and through chain 38 and sprocket-wheel 11 drives the feed-screw, so that the carriage traverses to the right. At the start the carriage is always 15 set to abut the left-hand bracket γ . The sections spirally laid on the reel, successively, in the warping operation are now all at once removed and beamed. When the beaming is completed the operator shifts 20 bracket γ clear of the filled beam and replaces it with an empty one, whereupon by manually turning backward the sprocket-wheel 11 the feed-screw is made to reset the carriage to its starting point for another 25 traverse; to avoid the noise of the clicking of the pawl over the teeth of ratchet 37 at this time he may lock back the pawl by means of pin 39. Occasionally it becomes necessary while a warp is in process of being beamed 30 to wind it back onto the reel from the beam. This is done by turning the reel backward by hand (the clutch between the pulley 17 and shaft 6 being then disestablished), and in order that there may be a corresponding 35 reverse traverse of the beam carriage the dog 35 is shifted into engagement with ratchet 37 and secured by its bolt 35', so that by bearing against the inclined face of one of the teeth of the ratchet it turns the latter and so 40 through the chain 38 rotates the screw 9 backward.

I obtain a more direct drive and greater simplification of structure by splining a part (as 14) of the gear train on the main shaft 45 6, and by journalling this shaft and the feed-screw on the one hand in the respective side portions (brackets δ) of the frame and on the other in the common support afforded by the cross-head σ , which connects and braces 50 the rods n forming the guideway for the carriage.

Heretofore when the beam was unshipped it was necessary to shift one entire end portion of the carriage away from the other in 55 order to clear the beam trunnion; by my invention the head ρ remains fixed and only its bracket γ is shifted.

Having thus fully described my invention, what I claim as new and desire to secure by 60 Letters Patent is:—

1. In combination, a frame including spaced members, a pair of horizontal guide-rods connecting them and a cross-head connecting said guide-rods and arranged between and spaced from said members, a

beam-carriage shiftable along the guide-rods and having supporting portions resting thereon one on each side of the cross-head, a drive shaft journaled in one of said members and the cross-head, and a transmission train 70 connecting the beam with said shaft and having one member thereof splined on the shaft and confined to the carriage to shift therewith.

2. In combination, a frame including 75 spaced members, a pair of horizontal guide-rods connecting them and a cross-head connecting said guide-rods and arranged between and spaced from said members, a beam-carriage arranged on and shiftable 80 along said guide-rods, a drive shaft journaled in one of said members and the cross-head, and a transmission train connecting the beam with said shaft and having one member thereof splined on the shaft and confined to the carriage to shift therewith. 85

3. In combination, a frame including a pair of spaced members, a reel journaled therein, a pair of spaced horizontal guide-rods connecting said members, and a cross-head connecting said guide-rods, and arranged between and spaced from said members, a beam-carriage arranged on and shiftable along the guide-rods, a beam journaled in the carriage, a drive shaft journaled in 95 one of said members and the cross-head, a feed-screw journaled in the other member and cross-head and having a threaded connection with the carriage, means to transmit rotary motion from said shaft to the beam, 100 and means to transmit rotary motion from the reel to the feed-screw on rotation of the reel from the rotating beam through the warp being beamed. 105

4. In combination, the frame, a horizontal rotary beam, means to support the beam in the frame, a rotary driven member journaled in the frame parallel with the beam, a transmission means connecting the beam and said member, a rotary driving member journaled 110 concentric with and rotative relatively to the driven member, a normally disestablished clutch to connect said members including a thrust device movable axially of said members, and means to control said thrust device including a lever fulcrumed on an axis parallel with the beam. 115

5. In combination, with the frame, a reel journaled therein, rotary beaming means, a going rotary driving member for the beaming means, and means, including a rotation-preventing device for the beaming means and a clutch device for operatively connecting the driving member and beaming means, movable to one position to secure the beaming means against rotation and disconnect the latter and driving member and to another position to release the beaming means and operatively connect the latter and driving means. 120 125 130

6. In combination, the frame, having a horizontal guideway, a beam, a beam-carriage in which the beam is journaled movable along the guideway, a reel journaled in the frame, means to rotate the beam, a feed-screw having threaded connection with the carriage and journaled in the frame, and means to transmit rotary motion from the reel to the feed-screw, said means including 10 rotary clutch members one coactive with the other to turn the screw in one direction but not in the other.

7. In combination, the frame having a horizontal guideway, a beam, a beam-car-

riage in which the beam is journaled movable along the guideway, a reel journaled in the frame, means to rotate the beam, a feed-screw having threaded connection with the carriage and journaled in the frame, and means to transmit rotary motion from the reel to the feed-screw, said means including rotary clutch members one coactive with the other to turn the screw in one direction but not in the other, and means to interlock said members for movement together in both directions.

In testimony whereof I affix my signature.

GEO. W. KUENNETH.
